UNITED STATES PATENT OFFICE

121,310

DESIGN FOR A WOVEN PILE FABRIC

William Wells, Firthcliffe, N. Y.

Application January 30, 1940, Serial No. 89,868

Term of patent 14 years

To all whom it may concern:

Be it known that I, William Wells, a citizen of the United States of America, residing at Firthcliffe, in the county of Orange and State of New York, have invented a new, original, and ornamental Design for a Woven Pile Fabric, of which the following is a specification, reference being had to the accompanying drawing, forming part thereof.

The figure is a plan view of a woven pile fabric showing my design.

I claim:

The ornamental design for a woven pile fabric, as shown.

WILLIAM WELLS.
